WINDOW CHANNEL

Adolph Rydquist, Rochester, N. Y., assignor
to The Schlegel Manufacturing Company,
Rochester, N. Y., a corporation of New York

Application August 21, 1934, Serial No. 740,789

30 Claims. (Cl. 296—44.5)

The present invention relates to window channels, such for example, as those employed for supporting or guiding windows or window panes in various vehicles, such as automobiles, aeroplanes, motorboats, and the like.

One object of the invention is the provision of an improved window channel or channel-like structure which is of simple construction and which can be manufactured at a relatively low 10 cost.

A further object of the invention is to provide a unitary window channel having improved and advantageous forms of construction which render it serviceable and efficient as supporting or 15 guiding means for a window or other form of closure.

A further object of the invention is to provide an improved window supporting or guiding structure designed for cooperation with a vehicle window when it is in substantially closed position to afford one or more ventilating openings whereby to insure an increase in the circulation of the air within or through the vehicle body to more 20 effectively ventilate the same.

A further object of the invention is the provision of a new and improved channel or channel-like structure formed of parts or sections which can be conveniently assembled and readily connected one with another whereby to provide a 25 unit for supporting either a fixed or a movable part such, for example, as a window or other closure.

A further object of the invention is the provision of an improved structural element designed 30 to serve both as cushioning means for a window and as means for connecting parts of a supporting or guiding structure for the window.

A further object of the invention is to provide an improved self-contained window channel 35 ready for direct application to a vehicle body and one which includes flexible parts permitting the channel to be readily bent or shaped to correspond to the shape of the window or other parts with which it may be associated.

To these and other ends the invention resides in certain improvements and combinations of parts, all as will be hereinafter more fully described, the novel features being pointed out in 40 the claims at the end of the specification.

In the drawings:

Fig. 1 is a view in elevation illustrating the application of the structure shown in Fig. 4 to a door or window frame in which the window 45 glass is lowered sufficiently to afford ventilating

openings between the upper corner portions of the glass and the frame;

Fig. 2 is a somewhat similar view illustrating the application of the modification shown in Fig. 10 to a window frame similar to that shown in Fig. 1;

Fig. 3 is a side elevation illustrating the application of the channel structure shown in Fig. 13 to a door or window frame corresponding to that shown in Fig. 2;

Fig. 4 is a side elevation of a window supporting or guiding structure embodying one form of the invention;

Fig. 5 is a cross section taken on line 5—5 of Fig. 4 and drawn to an enlarged scale; 15

Fig. 6 is an enlarged transverse section on line 6—6 of Fig. 4;

Fig. 7 is a view in perspective showing a portion of the main channel and one of the side members of the superimposed window receiving unit shown thereon in Figs. 10 and 12;

Fig. 8 is a view in perspective showing one end of the connecting strip for the side members of said unit;

Fig. 9 is a sectional elevation on line 9—9 of Fig. 8 drawn to an enlarged scale;

Fig. 10 is a side elevation of a slightly modified form of the invention;

Fig. 11 is a top plan view of the unit shown in Fig. 10 drawn to an enlarged scale; 30

Fig. 12 is a cross section on an enlarged scale taken on line 12—12 of Fig. 10;

Fig. 13 is a side elevation of another modification somewhat similar to that shown in Fig. 10;

Fig. 14 is an enlarged cross section on line 14—14 of Fig. 13, and

Fig. 15 is a horizontal cross section on an enlarged scale showing a window frame with the channel applied thereto, the parts being illustrated diagrammatically.

The same reference numerals throughout the several views indicate the same parts.

The channel of the present invention may comprise either a rigid or a more or less flexible body sufficiently stiff to be substantially self-supporting when placed in a window frame under normal conditions of use. In other words the main channel body may either be of an all metal construction or of fabric woven from non-metallic fibers, or it may include in part at least a metallic filament such as wires woven into the fabric to afford added stiffness without unduly decreasing the flexibility of the channel.

It will be understood that if it is preferred to construct the main channel entirely of metal, the 55

latter may, if desired, be of a nature which will permit it to be bent to afford different shapes depending on the shape of the frame or other parts with which it is to be associated.

5 This is true also of the connecting strip or securing element shown in Fig. 8 and employed as a means for uniting the side members of the structural channel shown in section in Figs. 6, 12, and 14, the different forms of which are shown 10 applied to the intermediate portion of the main channel in Figs. 4, 10, and 13, respectively.

Referring now to Fig. 1 of the drawings, there is shown at 10, for example, a vehicle door frame equipped with a window glass 11 arranged to 15 slide up and down to open and closed positions. In the position of the glass shown in Fig. 1 there are afforded the oppositely disposed ventilating openings 12 for increasing the circulation of the air within or through the vehicle body to effect 20 better ventilation of the same.

The door frame 13 shown in Fig. 2 is similar to that shown in Fig. 1, and has a window 14 free to be moved up and down therein which, when in the position shown, affords ventilating openings 25 15 at its upper corners.

Likewise the door frame 16 is provided with a sliding window 17 which when moved to the position shown affords ventilating openings 18 at its upper corner portions.

30 A cross section of one of the side members of the door frames shown in Figs. 1 to 3, inclusive, is illustrated more or less diagrammatically in Fig. 15 which affords an opening 19 for the insertion of the main window guide channel, shown generally at 20 and 26a in Figs. 4 and 10. The channel 20 comprises the oppositely disposed side portions 21 and the transverse connecting portion 22, Fig. 4.

The construction of the channel shown in Fig. 40 15 corresponds generally in cross section to the window channel described and claimed in the pending application of Charles P. Schlegel, Serial No. 660,402, filed March 11, 1933, (now Patent No. 2,012,354, granted August 27, 1935) which embodies a complete disclosure of the manner of 45 constructing this form of channel. The warp strands of the body of the channel are indicated diagrammatically at 23, and the transverse or weft strands, which may constitute metallic filaments, are indicated diagrammatically at 24. However, any of the strands may be made from either metallic or non-metallic material so that a part or all of the warp strands and a part or 50 all of the weft strands may be metallic if desired.

55 The channel body is preferably provided with suitable cushioning or lining means for supporting and cushioning the window or glass embraced by the channel and for providing a smooth runway for the glass if it is of the sliding or movable 60 variety. The lining means may be formed of pile or any other suitable cushioning material and may be formed as a part of the channel body or as a separate piece or pieces secured within the channel body as desired. Preferably the lining 65 comprises strips 25 of relatively long stiff pile woven integrally with the channel body, the strips extending longitudinally along the inner surfaces of the side portions and of the back or bottom portion of the channel, as indicated diagrammatically in Fig. 15.

The channel construction also includes relatively large warp strands 23a at its outer edges which serve to reinforce and enlarge said edges, the latter being embraced and protected by the 75 finishing or bead-like members 26 formed of sheet

or other suitable material and serving to stiffen the edges of the channel and maintain them in proper alignment.

The window 11, shown at Fig. 1, has an arched or rounded portion 11a at its upper end which, 5 when the window is completely closed, extends within the upper transverse connecting portion of the door frame in which position the rounded corner portions 11b of the window lie within the curved corner portions of the main channel 20. 10

In order to permit the window to be raised to full closing position in which it will serve to close the ventilating openings 12, the transverse connecting portion 22 of the channel is provided with an opening 27 in its bottom or horizontal 15 wall, Fig. 6, through which the arched portion 11a of the window is moved when elevating the window to its highest position.

Furthermore a receiving channel or channel-like member for the arched portion of the window 20 is superimposed upon the transverse connecting portion 22 of the window channel in registry with the opening 27 therein, said receiving member being indicated generally at 29 in Fig. 4. The receiving member is preferably made to correspond in shape to the upper arched portion 11a of the window as indicated by dotted lines in Fig. 1.

The opening 27 in the transverse connecting portion 22 of the main channel is preferably 30 formed by slitting said portion longitudinally and centrally thereof and bending outwardly the portions 30 into upstanding spaced relation, as best shown in Fig. 6. The outwardly bent portions are utilized as supporting means for the 35 channel-shaped window receiving member 29, the side walls 31 of each of which has its lower edge bent back upon itself and rebent to form a grooved or channel-shaped portion 32 for receiving the corresponding upstanding parts 30 of 40 the main channel, as best shown in Fig. 6.

The side walls 31 of the glass receiving member 29 are provided with laterally and inwardly extending spaced flange-like parts 33 lying opposite each other in pairs and beneath which is 45 extended a connecting strip 34 having a body portion of a width substantially equal to the distance between the side members 31 of the glass receiving member 29. The connecting strip 34 is provided with a series of laterally projecting 50 tongue-like securing members 35 at the opposite sides thereof which are extended through the openings 36 afforded by the spacings between the flange-like members 33 of the side walls of the window receiving member 29, said tongue-like 55 receiving members being bent into engagement with the exterior surfaces of said side walls, as shown in Figs. 4 and 6. The connecting strip 34 can be readily assembled in position between the walls 31 of the channel-shaped member 29 before the latter is connected with the main channel and united with said members to form a complete unitary structure which can be readily secured upon the main channel by positioning the grooved or channel-shaped portions 32 of 60 said unit upon the upstanding portions 30 of the transverse portion of the main channel 20, said channel-shaped portions being preferably clamped upon the supporting portions 30 to firmly secure the window receiving member upon 65 the main channel. The window receiving member 29 is also secured upon the main channel by means of the short extensions 37 on the ends of the connecting strip 34 which rest on the back 70 of the transverse portion 22 of the main chan- 75

nel, as shown in Fig. 4, and which are secured thereon preferably by means of the rivets 38, as shown in Fig. 5.

5 Cushioning means for receiving the arched portion 11a of the window 11 is secured within the recessed member 29 which preferably comprises a woven strip of fabric 39 shown diagrammatically in Figs. 6 and 9, which is provided with a cushioning pad 40 also indicated diagrammatically and preferably formed of relatively 10 long stiff pile suitable for obtaining the desired cushioning action. The pile is preferably interwoven with the strands of the strip 39 but may be otherwise connected with and supported by 15 said strip if desired. The woven strip 39 is formed of the warp and weft strands 39c and 39d, respectively, and is preferably provided with enlarged portions 41 at its opposite edges formed of one or more warp strands or cords 41c, as 20 shown in Fig. 9. The strip 39 is supported upon the inner face of the metal strip 34 by the inwardly turned portions 42 thereof which lie between the tongues 35 of the strip, as best shown in Fig. 8, said inwardly turned portions enveloping the enlarged portions 41 of the cushioning strip and also serving to lend the desired degree 25 of stiffness to the connecting strip which is formed of a relatively soft metal permitting the strip to be readily bent to any shape desired 30 whereby it may be made to conform to the shape or contour of the section or parts with which it is to be associated. The strips are preferably flat when completed and readily conform to the 35 contour of the curved edges of the side walls 31 of the member 29 when applied thereto.

The main channel shown in Figs. 2 and 10 is indicated generally at 20a and is provided with vertically extending side portions 21a and a transverse connecting portion 22a, the shape and 40 construction of this channel being the same as the channel 20 as previously stated. Either of the channels, as previously stated, may be formed entirely of sheet metal or other suitable material rather than of woven fabric, if desired.

45 The transverse portion 22a of the channel is provided with an opening 27a for the passage of the upper portion 14a of the window 14 shown in Fig. 2. The opening is preferably formed by slitting the base or back of the channel section 50 longitudinally of its center and turning outwardly the upstanding spaced portions 30a of the channel, as shown in Fig. 12. The channel is also provided with window cushioning pads 25a corresponding to the pads 25 of channel 20. The 55 window receiving member 29a, an enlarged plan view of which is shown in Fig. 11, is of substantially the same design as the member 29, and as many of the parts of the two designs are alike in construction, they have been given the same 60 reference characters with the addition of the letter a to the several parts of the member 29a, which will be readily understood from the description of the corresponding parts of the window receiving member 29.

65 However, it will be noted that there is a difference in the shapes of the members 29 and 29a, the former being curved as shown in Fig. 4, and the latter being flat on top for the greater portion 70 of its length and having a beveled or inclined portion 42a at one end thereof. A further difference between the two window receiving members in question is that the one shown in Fig. 10 does not have the securing parts 37 of the one shown in Fig. 4. It will be further understood 75 that the differences between the members

29 and 29a is due merely to the difference in the contours of the upper extremities of the windows 11 and 14, shown in Figs. 1 and 2, respectively.

The receiving member 29b for the upper portion 17a of the window 17 is shown in elevation 5 in Fig. 13 and by dotted lines in Fig. 3. Since the member 29b is substantially the same in construction as the member 29a, it has been given the same reference character with the exception that the letter b has been substituted for the letter 10 a in designating and describing the parts of the member 29b, it being understood that the description of the former will suffice for the latter, the one difference being that the channel-shaped members 32a at the lower edges of the side walls 15 31a are omitted from the side walls 31b of the member 29b, as will be seen from Fig. 14.

The lower edges of the side walls 31b of the window receiving member 29b are extended with- 20 in suitable anti-rattling members indicated generally by the reference character 43, Figs. 13 and 14. The anti-rattling member is formed of a metal section 44 bent back upon itself to afford a receiving channel for the side walls 31b of the member 29b and has a strip of woven textile fab- 25 ric 45 extending around its exterior surface and secured by bending the extreme edges of the metal sections down upon the edges of the fabric strip as indicated at 46. The woven fabric strips are provided on their inner faces with suitable 30 cushioning means for the window, such, for example, as the resilient pads 47 preferably formed of relatively long stiff pile woven into the textile strip 45 and projecting for a substantial distance therefrom. The cushioning means, however, 35 may, if desired, be formed and connected with the textile strip in any suitable manner other than that described. Preferably, however, the anti-rattling members 43 are constructed generally in accordance with the anti-rattling strips 40 or sections described and claimed in my copending applications, Ser. No. 697,315, filed November 9, 1933, for Window cushioning construction, and Serial No. 718,803, filed April 3, 1934, for 45 Anti-rattling strip.

The anti-rattling members 43 and the window receiving member 29b carried thereby form a unitary structure which may have its opposite ends placed in abutting relation with respect to and suitably connected with the ends of the op- 50 positively disposed channel members 21b which form a continuation of said unitary structure to afford cushioning and guiding means for the window 17, shown in Fig. 3, in which construction the central portion 17a of the window extends 55 within the receiving member 29b when the window is completely closed, in which position the ventilating openings 18 are also closed.

The channels 21b are preferably the same in cross section as the channels 20 and 20a, except 60 that the bead-like members 26 of the latter are omitted.

If preferred, the window receiving unit formed of the connected members 29b and 43 may be secured and supported within the door or window 65 frame 16 by the use of screws or nails driven through the relatively soft metal strip 34 into an overlying portion of the frame, not shown. The channels 21b may likewise be secured within the side members of the door or window frame 16 70 as shown in Fig. 15.

75 It will be understood that the metal strips 34, 34a, and 34b, similarly constructed in each of the designs shown in Figs. 4, 10, and 13, can be readily bent to correspond to the shapes or contours of

- the parts connected thereby and that they can be employed as a connecting means for other parts, not shown, having other shapes regardless of whether or not the cushioning strips 40, 40a and 5 40b are applied thereto. The metal strip, either with or without the window cushioning means comprises a useful and advantageous connecting element for oppositely disposed parts and affords a new and improved article of manufacture.
10. I claim:
1. A structural unit comprising a pair of metal strips angularly disposed one relative to another, one having spaced laterally projecting parts in overlying engagement with the other, the 15 latter having spaced tongue-like portions extending between said parts and bent down into engagement with a wall of the strip having said laterally projecting parts, the strip having the tongue-like portions also having angularly disposed parts engaging the other strip on the side thereof opposite that engaged by said tongue-like portions.
  2. A structural unit comprising oppositely disposed members, each of said members having spaced laterally projecting parts extending directions opposite to those on the other of said members, and a connecting element between said members having integrally formed securing portions extending between said parts and bent down 20 into engagement with the outer faces of said members, said element also having angularly disposed integrally formed portions engaging the inner faces of each of said members.
  3. A structural unit comprising oppositely disposed substantially parallel members each having spaced laterally projecting parts, said parts lying between said members, and a connecting element for said members extending therebetween and beneath said parts, said element having securing 25 portions projecting between said parts and bent down upon the outer faces of said members, said element also having integrally formed angularly disposed portions engaging the inner faces of said members at points between the securing portions 30 thereof.
  4. A substantially channel-shaped structural unit comprising oppositely positioned plate members each having spaced angularly disposed parts, the parts of one of the members lying opposite 35 the corresponding parts of the other member, and a connecting strip for said members extending longitudinally therebetween, said strip having securing portions projecting laterally therefrom in opposite directions between said 40 angularly disposed parts and bent down upon the outer faces of said plate members, said strip also having the edge portions thereof lying between the securing portions bent upon the strip and engaging the inner faces of said plate members.
  5. A substantially channel-shaped structural unit comprising oppositely disposed members each having spaced laterally projecting parts extending substantially at a right angle thereto, 45 said parts affording openings therebetween, a connecting strip between said members in engagement with said parts and having securing portions extending laterally therefrom through said openings and engaging the outer sides of said oppositely disposed members whereby to unite said members one with another, and channel-shaped parts formed on said members for the reception of supporting means for the unit.
  6. A structural unit comprising angularly disposed members, one having spaced laterally extending parts overlying the other and the latter having tongue-like portions extending between said parts and formed to engage one side of the member having said laterally extending parts 50 whereby to unite said members one with another, and a channel-shaped part formed on one of said members for the reception of supporting means for said unit.
  7. A structural unit comprising oppositely disposed plate members, each having a channel-shaped part formed thereon for the reception of supporting means for the unit, said plate members having spaced laterally projecting parts, said parts lying between said members, and a connecting strip for said members extending therebetween and beneath said laterally projecting parts, said strip having securing portions extending between said parts and cooperating with the sides of said plate members to connect one 55 with another.
  8. A structural unit comprising oppositely disposed members, each having a recessed part formed thereon, said members having spaced laterally projecting parts extending in opposite directions, a connecting element between said members having securing portions extending between the last mentioned parts and cooperating with said members to secure them against displacement one relative to another, and a channel-shaped member having portions thereof extending within said recessed parts and forming supporting means for said unit, said member having an opening for the passage of a window between said portions and between said oppositely disposed members.
  9. A structural unit comprising oppositely disposed members, each having a recessed part formed thereon, each of said members having spaced parts projecting laterally toward the other of said members, a connecting element between said members having securing portions extending between the last mentioned parts and cooperating with said members to secure them against displacement one relative to another, 60 and a channel member including side portions and a transverse connecting portion, said connecting portion being provided with spaced upstanding portions extending within the recessed parts of said oppositely disposed members and forming supporting means for said members.
  10. A structural unit comprising oppositely disposed members, each having spaced laterally projecting parts, a connecting element for said members extending therebetween and cooperating therewith to form an inverted channel, said element having securing portions extending between said parts and engaging the side walls of said members to connect one with another, said members having supporting parts thereon extending longitudinally thereof, and a channel member having side portions provided with a transverse connecting portion, the latter being disposed opposite said inverted channel, said transverse connecting portion having an opening 65 for the passage of a portion of a window therethrough into the inverted channel, said transverse connecting portion having spaced upturned members at opposite sides of the opening connected with the longitudinally extending supporting parts of said inverted channel and forming supporting means for the same.
  11. A window supporting channel for insertion in a window frame, comprising side portions having a transverse connecting portion, said con- 70

necting portion having an opening therein for the passage of a portion of a window, said connecting portion having spaced upstanding parts at the opposite sides of the opening for the 5 support of receiving means for said window portion.

12. A window supporting channel for insertion in a window frame, comprising side portions having a transverse connecting portion, said connecting portion having an opening extending longitudinally thereof and formed by slitting said portion and turning parts thereof outwardly in opposite directions for the support of receiving means for said window, and cushioning pads disposed interiorly of said channel for engagement with the opposite sides of the window.

13. A metal strip for connecting the side members of a channel, said strip having along each of two opposite side edges a series of laterally extending integrally formed tongues spaced from each other in a direction along said strip for engagement with said side members to connect one with another and also having along each of said two edges integrally formed inwardly bent 25 portions between said tongues for securing a cushioning element in position upon one face of the strip.

14. A metal strip for connecting the side members of a window channel, said strip having laterally extending integrally formed spaced tongues at each side thereof for engagement with said side members to connect one with another, a strip of fabric positioned on one face of said metal strip and having a cushioning pad for receiving a 35 portion of said window, and inwardly extending parts on the opposite edges of said metal strip formed integrally with the strip and extending between said tongues, said parts being bent downwardly upon said fabric strip and serving to 40 secure it upon said metal strip.

15. A window supporting structure for insertion in a frame, comprising a channel member having side portions provided with a transverse connecting portion, said connecting portion having an opening for the passage of a portion of said window, said opening being formed by turning parts of said connecting portion outwardly thereon, and receiving means for said window portion comprising a substantially U-shaped member, the 45 sides of which are secured upon the outwardly turned parts of said channel member.

16. A window supporting structure for insertion in a frame, comprising a channel member having side portions provided with a transverse connecting portion, said member having interiorly disposed window cushioning pads for engaging the opposite sides of the window, said connecting portion having an opening for the passage of an end portion of said window, said opening being 55 formed by turning parts of said connecting portion outwardly in opposite directions thereon into substantially parallel relation, receiving means for the end portion of said window comprising an inverted channel the sides of which are secured 60 on the outwardly turned parts of said channel member, and cushioning means for said window disposed interiorly of said inverted channel.

17. A window supporting structure for insertion in a frame, comprising a member having side portions provided with a transverse connecting portion, said member being substantially U-shaped in cross section and said connecting portion having an opening for the passage of a portion of said window, said opening being formed 70 by turning sections of said connecting portion

outwardly into substantially parallel relation, and receiving means for said window portion comprising an inverted channel the side walls of which have their free edge portions formed to afford substantially U-shaped parts within which the upturned sections of said member are secured. 5

18. A window supporting structure for insertion in a frame, comprising a member having side portions provided with a transverse connecting portion, said member being substantially U-shaped in cross section and having interiorly disposed cushioning means for said window, said connecting portion having an opening for the passage of a portion of said window, said opening being formed by turning sections of said connecting portion outwardly into spaced relation thereon, receiving means for said window portion comprising an inverted channel the side walls of which have their free edge portions formed to afford substantially U-shaped parts within which the upturned sections of said member are secured, and cushioning means for the upper edge of said window portion secured within said inverted channel. 10 15

19. A window guiding structure for insertion in a frame, comprising a channel having a body of woven material said channel being formed to provide side portions for receiving the vertical edge portions of the window, and the side portions having a transverse connecting portion, said connecting portion having an opening for the passage of an end portion of the window, said opening being formed by slitting said transverse portion longitudinally thereof and bending parts of said transverse portion into upstanding spaced relation, and a recessed member for receiving said window end portion when the latter is moved through said opening, said member having supporting parts therefor connected with and supported by the upstanding parts of the transverse 25 30 35 40 connecting portion of the channel.

20. A window guiding structure for insertion in a frame comprising a channel having a body of woven material including metallic strands woven into the body and extending transversely of the body to stiffen the same, said channel being formed to provide side portions for receiving the vertical edge portions of the window and the side portions having a transverse connecting portion, said connecting portion having an opening for the 45 50 55 passage of an end portion of the window, said opening being formed by slitting said transverse portion longitudinally thereof and bending parts of said portion into upstanding spaced relation, and a recessed member for receiving said window end portion, said member having supporting channels formed thereon within which the upstanding parts of said transverse channel portion are extended to form supporting means for said recessed member. 60

21. A window guiding structure for insertion in a frame, comprising a channel having a body of woven material, said channel being formed to provide side portions for receiving the vertical edge portions of the window and the side portions 65 having a transverse connecting portion, said connecting portion having an opening for the passage of an end portion of the window and having upstanding spaced parts at the opposite sides of said opening, a recessed member for receiving said window end portion, said member having supporting parts therefor connected with and supported by the upstanding parts of the transverse connecting portion of the channel, cushioning means for the window secured within the side 70 75

- portions of said channel, and means within said recessed member for receiving and cushioning the end portion of the window extending therein.
22. A window guiding structure for insertion in a frame, comprising a channel having a body of woven material including metallic strands woven into the body and extending transversely of the body to stiffen the same, said channel being formed to provide side portions for receiving the vertical edge portions of the window and the side portions having a transverse connecting portion, said connecting portion having an opening for the passage of an end portion of the window, said opening being formed by slitting said transverse portion longitudinally thereof and bending parts of said portion into upstanding spaced relation, and a recessed member for receiving said window end portion, said member having supporting channels formed thereon within which said upstanding parts are extended to form supporting means for said recessed member, cushioning pads for said window within said channel, and a cushioning pad for said window end portion secured within said recessed member.
- 25 23. A window supporting structure, comprising oppositely positioned spaced channels including side and angularly disposed end portions for receiving portions of a window, a channel-like structure between the angularly disposed portions of said channels in end to end relation with respect to said portions, said channel-like section including a part extending above the end portions of said channels for receiving a portion of the window extending above and lying between the portions received by the end portions of said channels, said channel-like section comprising side walls having inwardly extending spaced members thereon, and a connecting element between the side walls engaging said spaced members and having laterally projecting tongues extending between said members and cooperating with said walls to connect one with another.
24. A flexible strip for connecting the side members of a channel, said strip having laterally extending integrally formed spaced parts at each side thereof for engagement with the side members to connect one with another, a cushioning element positioned on one face of said strip, the latter having inwardly extending securing parts lying between said first mentioned parts and serving to secure said cushioning element upon the strip.
25. A flexible strip for connecting the side members of a channel, said strip having laterally extending parts at each side thereof for engagement with the side members to connect one with another, a flexible cushioning element positioned on one face of said strip and having bead-like portions at its opposite edges and a cushioning pad between said bead-like portions, said strip having inwardly extending securing members overlying the bead-like portions of the cushioning element and serving to secure the latter upon the strip.
- 65 26. A window guiding channel for insertion in a window frame, comprising side portions having a transverse connecting portion, said side and connecting portions having cushioning means on the oppositely disposed faces thereof, said transverse connecting portion having an opening for the passage of a portion of a window, and an inverted channel secured on said connecting portion and overlying said opening and adapted to receive the portion of the window moved through said opening.
27. A window guiding channel for insertion in a window frame, comprising side portions and a transverse connecting portion, said side and connecting portions having window cushioning strips disposed therein, said transverse portion having an opening for the passage of a portion of the window therethrough, an inverted channel overlying said opening, means connecting the inverted channel with the transverse portion of the guiding channel, and cushioning means secured within the inverted channel for receiving the upper edge of the portion of the window moved through said opening.
28. A window supporting structure, comprising oppositely positioned side channels having angularly disposed end portions spaced one from another, said channels and end portions being adapted to receive portions of a window, an inverted channel interposed between said end portions and connecting the same, said inverted channel having a portion thereof extending above the angularly disposed end portions of said spaced channels for receiving a portion of said window, and cushioning means for the window disposed within said inverted channel and the end and side portions of the first mentioned channels.
29. A window channel comprising a main channel-shaped section having a back wall and spaced side walls for receiving between them an edge of a window, and a supplementary section attached to said main section and extending throughout a part only of the length of said main section, said supplementary section including spaced side walls extending rearwardly from said main section and forming in effect a rearward prolongation of said side walls of said main section, at least a portion of said back wall of said main section being omitted adjacent said supplementary section so that an edge of a window may pass rearwardly through said main section and into said supplementary section.
30. A window channel comprising a main channel-shaped section having a back wall and spaced side walls for receiving between them an edge of a window, and a supplementary section attached to said main section and extending throughout a part only of the length of said main section, said supplementary section including spaced side walls extending rearwardly from said main section and forming in effect a rearward prolongation of said side walls of said main section, at least a portion of said back wall of said main section being omitted adjacent said supplementary section so that an edge of a window may pass rearwardly through said main section and into said supplementary section, and means forming relatively thick resilient cushioning pads adjacent the inner faces of said side walls of said main section.
